Term of patent 14 years

Int. Cl. D6—11

U.S. Cl. D12—203

FIG. 1 is a top plan view of an automobile floor mat embodying our new design.

FIG. 2 is a side elevational view of the mat.

FIG. 3 is a fragmentary vertical sectional view on an enlarged scale taken along line 3-3 of FIG. 1.

FIG. 4 is a fragmentary vertical sectional view on an enlarged scale taken along line 4-4 of FIG. 1.

FIG. 5 is a fragmentary vertical sectional view on an enlarged scale taken along line 5-5 of FIG. 1.

FIG. 6 is a fragmentary vertical sectional view on an enlarged scale taken along line 6-6 of FIG. 1.

FIG. 7 is a fragmentary portion of the top plan view on an enlarged scale of the area underlying line 7-7 of FIG. 4.

The pattern which is partially shown for ease of illustration is understood to be continuous throughout the area indicated. The undisclosed bottom is substantially flat and unornamented.

We claim:

The ornamental design for an automobile floor mat, substantially as shown and described.
